K. HAYASHI

PEN AND PENCIL HOLDER

Filed May 27, 1924

Fig. 1.

Fig. 3.

FIG. 2.

The diagram shows a horizontal metal strip with a segmented cross-section. The strip is labeled with a thickness of 1/16" and a width of 1/4". It is held in place by two clamps, one at each end. The left clamp is labeled 'C' and the right clamp is labeled 'F'. The strip is supported by a central support labeled 'B'. The entire assembly is labeled 'FIG. 4'. A dimension line indicates a total width of 1/4" for the strip. The strip is also labeled with '39' at the left end and '38' in the middle. The right end is labeled '37'.

UNITED STATES PATENT OFFICE.

KEN HAYASHI, OF CUMBERLAND, BRITISH COLUMBIA, CANADA.

PEN AND PENCIL HOLDER.

Application filed May 27, 1924. Serial No. 716,245.

To all whom it may concern:

Be it known that I, KEN HAYASHI, a subject of the Emperor of Japan, residing at Cumberland, Province of British Columbia, and Dominion of Canada, have invented 5 certain new and useful Improvements in a Pen and Pencil Holder, of which the following is a specification.

The present invention relates to improvements in pen and pencil holders adapted for holding a plurality of such instruments, and more specifically to a novel holder of the character described which may be readily attached to the pocket of a garment for holding pens or pencils contained therein against accidental displacement.

The primary object of the invention being to provide a novel pen and pencil holder for attachment to a pocket, embodying features whereby pens or pencils may be easily and conveniently inserted in the pocket, and there retained against accidental displacement.

A further object of the invention is to 25 provide a device of the character described whereby pens or pencils may be inserted or removed from the pocket to which the device has been applied with the use of one hand only.

A still further object of the invention is to provide a pen or pencil holder attachment for pockets whereby the upper portion of the pocket will be prevented from becoming worn, due to the placing and removing of writing instruments embodying fastening elements.

A still further object of the invention is to provide a novel holder for pens or pencils provided with attaching clips, embodying means whereby the clip of the pen or pencil will be securely held between gripping members for retaining the instruments in adjusted position, and means whereby the gripping members may be moved to a released position for permitting of the ready withdrawal of the implements therefrom.

Other objects and advantages of the invention will appear in the following detailed description, taken in connection with the accompanying drawing, forming a part of this specification, and in which drawing,

Figure 1 is a perspective view of my improved holder.

Figure 2 is a front elevation of the holder shown attached to the upper portion of a

pocket and showing writing instruments carried thereby.

Figure 3 is an end view of the same with one of the end plates removed for disclosing details of construction.

Figure 4 is a top plan view of the holder and

Figure 5 is a rear elevation of the same.

Referring to the drawing in detail, and wherein like characters designate corresponding parts throughout the several views, A designates my improved pen or pencil holder comprising a main body portion B adapted for connection to a garment pocket or any desired article as by means C; D means for yieldably engaging the clip of a pen or pencil; and E means for operatively connecting the gripping means D with a release mechanism F.

Referring to the body portion B, the same preferably consists of a longitudinally recessed lower body portion 10 provided with an upwardly extending rear wall 11. The rear wall of the lower body portion 10 is formed with depending arms 12 adapted for threaded reception of the connecting means C, while the depending front wall 13 is formed solid for presenting a neat appearing front to the device and forming an abutment for co-action with the means C. The upwardly extending wall 11 has formed at its upper end, an inclined outer face 14 which is concaved at its lower portion as at 15 for providing a longitudinally extending retaining edge 16. The upper edge 17 of the inclined face 14 terminates in a plane adjacent the rear face of the wall 11 in a manner for readily guiding the clip of a pen or pencil into operative relation with the means D.

The means C for connecting the holder A to the upper portion of a pocket, preferably consists of thumb screws 18 having the screw threaded shanks 19 thereof, which extend transversely in the recess of the lower body portion 10, adapted for threaded engagement with the depending arms 12. A clamping disc 20 is swivelly mounted at the forward end of each thumb screw 18 for firmly clamping the material of the pocket against the inner face of the front wall 13 as is clearly shown in Figure 3.

The yieldable means D for gripping the clip of a pen or pencil, consists of an elongated latch 21 being rigidly connected at its lower end to a longitudinally extending

shaft 22 which is rotatably mounted in the lower body portion 10 as by bearings 23. A right angularly extending arm 24 which is rigidly secured to one end of the shaft 22 is adapted for co-action with the means E for moving the latch 21 out of operative relation with the retaining edge 16. Coil springs 25 disposed at opposite ends of the shaft 22 are adapted to act upon the latch 21 for normally urging it toward the retaining edge 16. The gripping head 26 of the latch 21 is formed with an inclined inner face 27 for providing a V-shaped groove whereby the ball end of the pencil clip will be readily guided into a locked position beneath the retaining edge 16, and a hook portion 28 of the latch head 26.

The means E for operatively connecting the means D with the release mechanism F consists of a toothed wheel 29 adapted for co-meshing relation with a segmental toothed wheel 30. These co-meshing wheels 29 and 30 are disposed in a recess 31 provided at one end face of the main body portion B; and provided at the outer face of the segmental wheel 30, which is rotatably mounted on the shaft 22, is a stop 32 which is adapted to move in an arcuate path and engage the arm 24 when a downward movement is imparted to the means F.

Referring to the releasing means F, the same preferably consists of a slidable push rod 33 which is vertically mounted in guides 34, and a coil spring 35 for normally urging the rod upwardly to a home position. A toothed rack 36 provided adjacent the inner end of the rod 33 is adapted to engage the toothed wheel 29 for imparting movement to the yieldable means D when the rod 33 is pressed inwardly as by pressure upon the button 37.

It will therefore be seen that when the push rod 33 is pressed inwardly, that a rotary movement will be imparted to the segmental wheel 30, through the co-meshing rack 36 and toothed wheel 29. As the segmental wheel 30 rotates, the integrally formed stop 32 will be caused to engage the arm 24, and upon further movement will cause the arm to swing upwardly thereby swinging the latch head 26 out of operating relation to the retaining edge 16 and permitting of the ready withdrawal of the clip from between the gripping members; since as before stated the means D is rigidly secured to the shaft 22. The object for rotatably mounting the segmental wheel 30 upon the shaft 22, is to permit of the latch head 26 to swing outwardly as when the ball end of a clip is moved into position beneath the hook 28 and edge 16, without imparting movement to the means E and release mechanism F.

End cover plates 38, one of which forms

are provided with yieldable rings 39 for receiving pens or pencils not provided with retaining clips.

It can therefore be seen that a pen or pencil may be readily removed from the holder with one hand by merely grasping it with the thumb and index finger, while exerting a slight pressure on the button head 37 with a middle or ring finger.

Changes in detail may be made without departing from the spirit or scope of my invention; but.

I claim:

1. A holder of the class described comprising a body portion provided with a retaining edge, a latch head mounted on said body portion and adapted for movement toward and away from said retaining edge, means reciprocally mounted on the body portion and operatively connected to the latch head for moving the latch head out of operative relation with the retaining edge, and means for normally urging the latch head into operative relation with said retaining edge.

2. A holder of the class described comprising a body portion provided with a longitudinally extending retaining edge, yieldable means pivotally mounted on said body portion including an elongated latch head adapted to be normally urged toward said retaining edge, release means for swinging the latch head out of operative relation with said retaining edge, and means for automatically returning the release means to a set position.

3. A holder of the class described comprising a body portion provided with a retaining edge, a shaft rotatably carried by said body portion and having a right angularly extending arm formed at one end thereof, a latch rigidly carried by said shaft, means for normally urging the latch toward said retaining edge, a push rod slidably carried by said body portion, means for normally urging the push rod to a set position, and means operatively connecting the latch with said push rod, embodying a stop adapted to engage the arm on said rod for swinging the latch away from said retaining edge when the push rod is moved inwardly.

4. A holder of the class described comprising a body portion provided with a retaining edge, a shaft rotatably carried by said body portion and having a right angularly extending arm formed at one end thereof, a latch rigidly carried by said shaft, means for normally urging the latch toward said retaining edge, a segmental toothed wheel rotatably carried by said shaft provided with a stop adapted to engage said right angular arm, a push rod slidably carried by the body portion and having a toothed rack provided adjacent its inner end, means for normally urging the push rod

to a set position, and a toothed wheel co-meshing with the rack and segmental wheel whereby said stop will be caused to engage said right angular arm for swinging the latch to a released position when said push rod is forced inwardly.

5. A holder for pens or pencils provided with attaching clips comprising a U-shaped body portion adapted for connection to the upper portion of a pocket, a wall extending upwardly from the body portion provided with an inclined outer face being concaved at its lower portion and providing a longi-

tudinally extending retaining edge, a latch pivotally carried by the body portion and 15 having an inclined inner face terminating in a hook portion disposed in confronting relation with said retaining edge, means for yieldably urging the latch toward the retaining edge of said wall, and operable 20 means for swinging the latch out of operative relation with said retaining edge for permitting of the withdrawal of a pen or pencil clip from the holder.

KEN HAYASHI.
